(57) **CLAIM**

The ornamental design for a lid for drink bottle, as shown and described.

DESCRIPTION

FIG. 1 is a top front perspective view of a lid for drink bottle, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a top front perspective view thereof, with the lid opened for clarity of disclosure.

The broken lines shown in the drawings illustrate portions of the lid for drink bottle that form no part of the claimed design.

1 Claim, 8 Drawing Sheets
